DOUBLE SEAM - QUALITY CHECKS

CRITICAL PARAMETERS	OPERATIONAL PARAMETERS		FIRST OPERATIONS		BEST PRACTICES		
	SEAM THICKNESS	FREE SPACE	SEAM THICKNESS FIRST OP	SEAM LENGTH FIRST OP	SEAM SINKAGE	SEAM SINKAGE	
SEAM THICKNESS	 SPEC. WT. = 0.0022	 SPEC. WT. = 0.0022	 All measurements must be taken immediately after welding or processing may affect the seam results.	 SPEC. WT. = 0.0022	 Empty and fine bore, before double seam check.	 before double seam check.	
TIGHTNESS RATING	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	
COUNTERSINK DEPTH	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	
ACTUAL OVERLAP	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	 SPEC. = 0.0035 ± 0.0022	
BODY HOOK BUTTING	 FORMULA SPEC. = 100%	 FORMULA SPEC. = 100%	 FORMULA SPEC. = 100%	 FORMULA SPEC. = 100%	 FORMULA SPEC. = 100%	 FORMULA SPEC. = 100%	
SEAM GAP	 SPEC. = 0.0024"	 SPEC. = 0.0024"	 SPEC. = 0.0024"	 SPEC. = 0.0024"	 SPEC. = 0.0024"	 SPEC. = 0.0024"
